CLAIM

The ornamental design for a cleaning system trolley, as shown and described.

DESCRIPTION

FIG. 1 is a perspective view of a cleaning system trolley constructed in accordance with an embodiment of the present invention;

FIG. 2 is a left side view of the cleaning system trolley shown in FIG. 1;

FIG. 3 is a right side view of the cleaning system trolley shown in FIGS. 1 and 2;

FIG. 4 is a front view of the cleaning system trolley shown in FIGS. 1-3;

FIG. 5 is a rear view of the cleaning system trolley shown in FIGS. 1-4;

FIG. 6 is a top view of the cleaning system trolley shown in FIGS. 1-4; and,

FIG. 7 is a bottom view of the cleaning system trolley shown in FIGS. 1-6.
